Primary Examiner — Ryan Harvey(74) *Attorney, Agent, or Firm* — UB Greensfelder LLP; Benjamin D. Rotman(57) **CLAIM**

The ornamental design for a quadriceps and hip flexor training table, as shown and described.

DESCRIPTION

FIG. 1 is a front perspective view of a quadriceps and hip flexor training table in accordance with the invention;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIGS. 1; and,

FIG. 7 is a bottom view of FIG. 1.

The broken lines in the figures illustrate the portions of the design that form no part of the claimed design.
